United States Patent Office

Des. 219,525
Patented Dec. 22, 1970

219,525

MODEL RACING CAR

Ronald Sidney Tauranac, Weybridge, England, assignor to Motor Racing Developments Limited, Weybridge, England

Filed Oct. 13, 1969, Ser. No. 19,525

Term of patent 7 years

Int. Cl. D21—02

U.S. Cl. D34—15

FIG. 3

FIG. 1 is a top plan view of the model racing car,
FIG. 2 is a front elevation,
FIG. 3 is a side elevation,
FIG. 4 is a rear elevation.

The opposite side of FIG. 3 is identical to the side shown.

I claim:

The ornamental design for a model racing car, as shown and described.
